(57) **CLAIM**

The ornamental design for a shoe iron, as shown and described.

DESCRIPTION

FIG. 1 is a quartering perspective view of a shoe iron of the present design.

FIG. 2 is a top view of the embodiment of FIG. 1.

FIG. 3 is side view of the embodiment of FIG. 1.

FIG. 4 is a side view of the embodiment of FIG. 1, of the side opposite that shown in FIG. 3.

FIG. 5 is a bottom view of the embodiment of FIG. 1.

FIG. 6 is a front view of the embodiment of FIG. 1; and,

FIG. 7 is a rear view of the embodiment of FIG. 1.

The broken lines shown in the drawings represent portions of the shoe iron that form no part of the claimed design.
